Filed Feb. 19, 1959, Ser. No. 794,302

17 Claims. (Cl. 34—114)

The present invention relates generally to an apparatus for the manufacture of paper but relates more particularly to the drying aspects thereof.

In the paper-manufacturing industry it is the conventional practice to form from the pulp stock a sheet or continuous web of material. The conventional paper-making machine comprises a drying section provided with a large number of internally heated drying rolls, the purpose of which is to dry or evaporate the excess moisture from the web to a predetermined minimum content. In a modern high-speed paper-making machine it is necessary to evaporate thousands of pounds of water per minute in the form of water vapor and to conduct the same away from the immediate vicinity of the drying section.

In order better to control the air conditions immediately surrounding the drying section, it has for many years been the practice to provide a canopy-type hood which partially surrounds the drying section. This type hood comprises a roof and side and end walls which depend therefrom, thus enclosing the upper part of the drying section but leaving the lower part open. It has also been the practice to provide suitable fans to exhaust the water vapor and air mixture and to discharge it to the outside atmosphere or to other process apparatus which will extract part of the heat and water vapor for purposes of economy. Such constructions are of some help in increasing efficiency but leave much to be desired.

There have also been some installations wherein the drying section of the paper-making machine has been fully enclosed; that is to say, such hoods comprise a roof panel together with side walls which reach from the roof entirely to the mill floor.

In order to permit access to the drier section, especially from the operative side of the machine, some constructions have provided vertically movable doors closing substantially the lower half of the side wall. These doors, in operation, are normally lowered and in contact with the mill floor, the doors having relatively small observation windows to permit the operator to observe the drying section. When it is necessary to have access to the drying rolls these doors must be raised, and for this purpose it has been customary to provide operating mechanism comprising cables, line shafts, electric motors, framing mechanisms in which the doors can slide, and many other parts, together with controls permitting the raising of either one or more doors or the entire group of doors that form the bottom closure for one side of the drying section of the machine.

Such a fully enclosed hood has several advantages over the partially enclosed hood earlier described in that the condition of the space within the hood may be more accurately controlled.

However, because of the number and complexity of the parts, the initial cost is relatively high. Furthermore, even though there be safety devices, there is always danger of the sliding doors binding or some other parts becoming inoperative at the very moment when the paper

2

web, passing through the drier section at high speed, breaks, and hence requires instantaneous attention by the operator to prevent damage to the machine.

At times it is necessary to remove some of the doors for repair work or for removing all of the doors and associated equipment in order to permit the removal and replacement of the drier rolls.

In addition to the fully enclosed hood referred to above, there has been on the market for many years another type of full closure for the drying section of the machine. This last mentioned type of closure is one requiring such a fine fitting of the parts as will enable the generation of a high vacuum within the closure. This construction has not been used to any great extent because of the relatively high cost of the closure since it is necessary to create a powerful vacuum and to provide an efficient condenser to maintain a vacuum within the hood closure.

One of the objects of the present invention is to provide apparatus for use in the manufacture of paper for the purpose of drying the paper and which, while efficient in operation, will be of such construction that it can be produced, installed, and operated at relatively low cost, and which will enable the operator at all times to have full and substantially unobstructed view of at least the lower part of the operative part of the drier machine or section.

Another object of the invention is to provide apparatus of this type which can be used in conjunction with various types of paper-drying machines or the drying sections of conventional paper-making machines.

Again it is an object of the invention to provide a novel apparatus for the control of the air temperature and humidity conditions surrounding the drier section of a paper-making machine, which apparatus shall be simple in operation and effective in use.

A more specific object of the invention is to provide a closure for use with a paper-drying machine or section which will provide means for supplying the major portion of the air for the drying operation to the drier section from one or more sources and to provide a relatively high velocity air curtain on at least one side of the machine, the air curtain being blown across an opening between the mill floor and the lower margin of at least one of the closure's side walls, together with means for exhausting from the upper interior portion of the closure all the air supplied to the closure, together with the water vapor resulting from the drying operation, and to maintain such balance in the space within the closure with that of the mill area exterior of the closure as to prevent more than a relatively small amount of air flowing from the mill into said closure through the air curtain.

A still further object of the invention is to provide closure means of the kind described, wherein the major quantity of air supplied to the closure is heated to facilitate the drying operation.

The manner in which the above and other objects are attained will appear as the specification proceeds.

The invention will be particularly described in connection with a typical drying section of a high-speed paper-making machine but this, it should be understood, is by way of illustration and not by way of limitation, since the invention may be used with advantage in other types of paper-drying machines in the manufacture of paper.

In the drawings:

Figure 1 is a diagrammatic view in perspective elevation of that portion of the closure structure which extends above the mill floor, the same being shown in its relation to the drying section of a paper-making machine.

Fig. 2 is a transverse vertical sectional view substantially on the line 2—2 of Fig. 1 but on a somewhat larger

scale and also showing part of the apparatus which is disposed in space underlying the mill floor.

Fig. 2A is a fragmentary transverse vertical section similar to the upper portion of the left-hand side of Fig. 2 but illustrating a modified construction.

Fig. 3 is a transverse longitudinal section substantially on a line 3-3 of Fig. 2, viewed in the direction of the arrows but upon a smaller scale.

Fig. 4 is a view similar to Fig. 3 but taken along the line 4-4 of Fig. 2.

Fig. 5 is a fragmentary view on an enlarged scale of a part of the mill floor, a portion thereof being broken away to show one of the blower elements which is used to supply high velocity air to discharge openings in the mill floor to constitute a substantially continuous air curtain extending across the open area below the bottom portion of one of the closure side walls and the mill floor.

Fig. 6 is a perspective view of a blower unit air trunk section, a number of which can be provided for supplying the high velocity air to constitute the substantially continuous air curtain.

Fig. 7 is a view in elevation substantially on the line 7-7 of Fig. 2, but on a smaller scale, showing a modified construction in which the air curtain arrangement is omitted from that side of the machine.

Fig. 8 is a fragmentary view of one end of a drying roll showing a modified feature, and

Fig. 9 is a view on the line 9-9 of Fig. 8.

General description of the invention

There is involved a paper-drying machine which, in practice, is a section of a paper-making machine. The paper web, as it leaves the wet end of the paper-making machine, enters the drier section, there passing over a considerable number of hot rolls usually heated by steam admitted to the interior of the rolls. The dried web leaves the opposite end of the drier section in accordance with known practice.

The present invention in one form comprises a closure for the paper-drying section and includes a roof portion, end walls, and side walls which depend from the lower outer marginal portions of the roof portion, terminating at a level substantially above the mill floor, thus providing openings at each side of the machine extending substantially the entire length of the drying section.

This arrangement permits continuous observation of the drying machine. Passages are always available for the operator to gain instant access to the machine should conditions so require.

Means are provided to exhaust from the upper portion of the closure, as by power-driven and controlled exhaust fans, the large volumes of air which enter the closure for paper-drying purposes as well as the substantial volume of water vapor resulting from the drying operation.

In the illustrated form of the invention the drier section comprises a major portion which extends above the mill floor, and a minor portion located below the mill floor, there being an opening through the mill floor over which the major portion of the drier section is positioned.

Below the mill floor there is provided blower means for supplying a major part of the air to the drier section together with means for heating this air prior to its passage through the mill floor opening, thereby increasing the drying capacity of the air.

As shown, the said blower means is arranged to discharge into what may be termed a plenum chamber formed by two end walls and two side walls, the latter extending the full distance between the end walls. All of said walls extend from the underside of the mill floor to the next floor below or some other floor-like struc-

ture serving to close the bottom of the so-called plenum chamber.

Additionally, the invention comprises means for establishing and maintaining a substantially continuous air curtain located at each side of the drier section of the machine extending substantially the entire length thereof and flowing upwardly so as to traverse the opening between the lower marginal portions of the closure side walls and the mill floor.

10 In the form of the invention illustrated, the air curtain is provided by a plurality of motor-driven blowers connected to discharge high velocity air through a plurality of slots in or adjacent the mill floor and extending longitudinally of the closure below the side walls of the closure. Means are provided whereby the air forming the air curtain is heated to aid in effecting the web-drying operation.

In the form shown the major part of the air for drying purposes flows through the opening in the mill floor 20 and, while large in volume, is of relatively low velocity as compared with the air discharging from the slots to form the air curtain; that is to say, the air discharging from the slots to form the air curtain is of relatively high velocity and of relatively low volume as compared 25 to that of the major air flow.

Means are also provided to control the volume of air and moisture vapor exhausted from the closure per unit of time, which is obviously related to the conditions within the closure, the same being dependent upon the 30 speed of the web passing through the drier section, the amount of moisture in the web, the amount to be evaporated by the drier, etc.

Means are also provided for the control of the amount, volume, and velocity of the air supplied by the blower 35 means which furnishes the major part of the air as well as that supplied to produce the air curtains.

The various means for supplying air to and removing it and the water vapor from the closure are operatively controlled to maintain such balance inwardly and outwardly of the closure as will prevent more than a relatively small volume of air from passing through the air curtains.

40 In a modified arrangement the closure is provided with an air curtain only on one side, the other side being closed from the roof portion to the mill floor and being provided with sliding doors to permit access to the drying machine.

45 There are further details and modifications but the foregoing general description will facilitate an understanding of the invention.

Further and more detailed description of the invention

With particular reference to Figs. 1 and 2, the closure comprises roof section 20, longitudinal side walls 21 and 22, and end wall portions 23 and 24, which parts are mounted over and preferably supported by steel framework S connected to and extending from the upper part of the machine frame F.

The drying machine shown is typical of the drying section of a high-speed paper-making machine. It comprises a plurality of drying cylinders C mounted for rotation in the machine side frame F. One of the cylinders CL is located below the mill floor M and the others mainly above the mill floor. An opening O communicating the closure above the mill floor with the space below the mill floor extends substantially the entire length of the drier section and, as will be explained in detail later, serves in the arrangement illustrated to provide the major portion of the air to the drier machine closure for drying purposes.

70 The roof portion 20 is substantially equal in length to that of the machine and is greater in width, thus providing portions which extend beyond the machine at each side. The side walls 21 and 22 are substantially coextensive in length with the roof 20, and extend from

the roof, eaves, or side marginal portions downwardly to a plane substantially halfway between the roof, eaves, and the mill floor, thus providing an elongated substantially rectangular area extending from one end wall to the other end wall. This opening, as clearly appears in Fig. 1, provides an unobstructed view of the lower part of the drying machine and also provides for the unobstructed access by the operators to the area closely adjacent the drier machine side frames.

The structure thus described provides enclosure for the top and a partial closure for the sides of the machine, together with closures formed by the opposite end walls, which extend from the roof downwardly to the mill floor, except for transverse openings necessary to permit entry and exit of the paper web to and from the drying machine.

Communicating with the upper portion of the closure is a plurality of exhaust ducts 30, each connected with a motor operated exhaust fan 40 and serving as means for exhausting air and vapors from the upper portion of the closure.

Since it is desirable that the major part of the air for drying purposes be supplied to the closure under properly controlled conditions, means are provided for that purpose.

Means for supplying major part of air to machine closure

The means here shown for supplying the major part of the air for drying purposes will be best understood by reference to Figs. 2 and 3, wherein SF represents a sub-floor located a substantial distance below the mill floor M. Extending between the bottom side of the mill floor M and the sub-floor SF are four upright walls, i.e., two end walls 42 and 43 and two side walls 44 and 45, the latter extending from end wall to end wall (see Fig. 3) and thus forming, with the sub-floor SF, the mill floor M, and the opening O an open top chamber AC communicating with the drier section which extends above the mill floor.

As here shown, the side walls 44 and 45 are spaced outwardly of the vertical structural members 50 which support the drying machine. Since the drying machine is or may be of conventional construction, parts thereof are shown only by broken lines which will suffice to indicate the relationship of the machine to the closure and associated mechanism.

In order to permit access to the chamber AC the side walls are provided with a plurality of doors 51.

For supplying a major part of the air for drying purposes, there is provided a plurality of blowers 53, each driven by a separate electric motor 54.

In order to provide heated air for discharge by the blowers 53, a heater 55 is provided and which communicates with the blower intake. By the described means a large volume of heated air is supplied to the chamber AC underlying the mill floor and to that part of the drying machine which extends upwardly of the mill floor through the mill floor opening O.

The apparatus for providing the air curtains

This apparatus will be best understood by reference to Figs. 2, 4, and 6.

As will be observed in Figs. 1, 2, and 4, there is provided in the mill floor M a plurality of slots 60 which extend longitudinally below the side walls of the closure. Preferably, there is provided a plurality of air trunk sections in operative alignment, one of which is shown in detail in Fig. 6. Each section comprises a duct 61, a blower 62, and an electric motor 63 for operating the blower. The blower discharges into the duct 61, the air discharging upwardly through a plurality of relatively narrow tubes 64, each of which is provided with a damper 65 to control the direction of flow of the discharged air.

As best shown in Fig. 2, the intakes of the blowers 62 are located in the chamber AC below the mill floor. Since the air in this chamber is heated by the blowers

which supply the air to the chamber, it is obvious the air discharging from the tubes 64, which are positioned to extend into the slots 60 in the mill floor, will also be heated. If desired, separate means can be provided to supply heated air to the ducts 61.

By making the ducts in sections, the air supply can be controlled individually to each section by means which will be described later. These sections also facilitate adapting the air supply to the varying structural features of the building.

The velocity of the air discharging from the slots to form the air curtains is relatively high; that is to say, the velocity is much greater than that of the air flowing through the opening O and which provides the major portion of air for drying purposes.

Modified means for providing air curtain

In some instances, particularly in old installations, the structural arrangement of the mill may be such as to preclude the locating of the air ducts below the mill floor.

In Fig. 2A there is shown an arrangement wherein the elongated air duct 61M is located above the mill floor and adjacent the machine frame. It is provided with a plurality of adjustable air discharge tubes 64M arranged to form an air curtain as before described. It will, of course, be understood that means are provided to supply air to the duct 61M under pressure as required to form the high velocity air curtain.

Modification in which one side of machine is fully closed

In the arrangement previously described, both sides of the drying machine are provided with air curtains. However, in general, it is sufficient to provide an air curtain on one side only. In such an arrangement the air curtain is provided on what is termed the working or operative side of the machine; that is to say, the part of the machine which must be constantly watched and to which quick access is necessary in an emergency. When the open area is provided along one side only and the air curtain there established and maintained, the side wall on the other side of the machine is extended to the mill floor. Such an arrangement is shown in Fig. 7.

In this instance the one side wall is provided with a plurality of horizontally sliding doors 70 in the upper part of the side wall and a plurality of horizontally sliding doors 71 in the lower part. By sliding the door longitudinally of the side wall, access may be gained to any part of that side of the machine. Since the opposite side of the machine is provided with an open lower area traversed by an air curtain as before described, it is obvious that access can be had continuously to that side of the machine as well as the ability to observe the entire lower part of that side of the machine during operation.

The modification shown in Figs. 8 and 9

It will be appreciated that the drying rolls are highly heated. Hence some of the radiant heat from the portions of the rolls or cylinders in the area of the air curtain would pass into mill area outside the closure.

Various means can be provided to prevent or minimize this action. In Figs. 8 and 9, there is shown one means for this purpose. Therein 80 represents a fragmentary part of one end of the hot roll, 81 represents a part of the machine frame, and 82 represents one of the cylinder journals having a bearing in the frame to permit the necessary rotation of the hot cylinder during operation.

Located between the machine frame 81 and the adjacent end of the cylinder 80 is a disc structure 83. The disc 83 is formed of two halves 83A and 83B so that it can be put in place and clamped by means of the flange portions 84 and the removable fasteners 84F.

The disc 83 is held in spaced relation with respect to the end of cylinder 80 by means of a plurality of circumferentially spaced leg portions 85.

As shown, the disc 83 is provided with a plurality of

air openings 86 and a plurality of radial vanes 87 so that, in the rotation of the cylinder, air is caused to circulate in the space between the cylinder end and the confronting face of the disc.

The disc 83 is preferably made of a bright metal, such as stainless steel, and the face confronting the end of the cylinder 80 is preferably provided with a black coating 88 for heat-absorbing purposes.

Conveniently, the disc may be provided with a man-hole member 89 positioned over the usual manhole cover 10 usually found in the end of the drier rolls.

The control panel

Referring to Fig. 1, there is provided preferably adjacent one end wall of the drying machine closure an 15 electrical control board or panel 90. This control board contains a plurality of switches 92 wired and connected to control the various motors for operating the blowers which supply the major part of the air for drying purposes, the motors which operate the blower, which supply the high velocity of air to establish and maintain the air curtains, and the motors for operating the exhaust blowers. The electrical arrangement is such that any or 20 all motors operating the blowers for supplying the major part of the air can be started or stopped at will; also, any or all of the motors for operating the blowers providing the high velocity air for the air curtains can be started and stopped at will, and the like control is provided for the motors that operate the exhaust fans.

The operation of the various motors, the electrical 30 controls therefor, and the positions of the dampers or other means governing the velocity and volume of air discharging into the closure, and the air and vapor exhausted from the closure is such that a substantial balance is maintained within the closure and in the mill adjacent the side walls so that not more than a relatively small amount of air can pass through the air curtain. In practice, it may be advisable to permit a relatively small amount of air to pass through or into the air curtains to assure against the discharge of moist air from 40 the drier into the adjacent portions of the mill.

The air curtain air, as it passes upwardly, preferably strikes the solid inner side wall of the closure just above the lower marginal portion thereof and, because of its high velocity, will tend to follow along the inner side 45 face for some distance. This, to a certain extent, acts as an insulator and, in any event, prevents the curtain air from passing into the mill area outside the closure.

I claim:

1. Apparatus for use in combination with a paper-drying machine having at least a substantial portion extending upwardly of a mill floor, said apparatus comprising a roof extending over the top of the machine and being of greater width than at least that portion of the machine which extends upwardly of the mill floor so that the roof extends beyond each side of said last-mentioned portion of the machine, end walls positioned at the ends of the roof portion, one end wall having an opening to provide for the entry of the web to and the other an opening for the exit of the web passing from the machine, longitudinal side walls substantially coextensive in length with the said roof and joining said end walls at each end, at least one of said side walls extending from adjacent the outer marginal side portion of the roof and terminating in a plane substantially above the mill floor, thereby providing an open area between the lower margin of that side wall and the mill floor which is substantially coextensive in length with that of the said side wall, means for supplying air at relatively high velocity, air outlet means positioned longitudinally of the said side walls substantially coextensive in length with the said open area, being adjacent the mill floor and being arranged to discharge air upwardly in the form of an air curtain, means communicating said air-supplying means with said air-outlet means whereby the curtain of air moves at rela-

tively high velocity across said open area in a direction to pass inwardly of the outer face of the adjacent side wall, other means for supplying a major part of the drying air to the machine, means for exhausting from the upper interior portion of the roof and walls air supplied by said major air-supplying means and the air supplied to form said air curtain together with the water vapor resulting from the drying operation, all said means being formed and adapted to supply air in such volume and velocity as to maintain such a balance between the space within and the air forming outwardly of said open area below the side walls that the air passing out the exhaust means is comprised mainly of that supplied by said major air-supplying means and said curtain.

2. The arrangement set forth in claim 1 together with means for heating the major part of the drying air.

3. The arrangement set forth in claim 1 together with means for heating the air forming the air curtain.

4. Apparatus for use in combination with a paper-drying machine having at least a substantial portion extending upwardly of a mill floor, said apparatus comprising a roof extending over the top of the machine and being of greater width than at least that portion of the machine which extends upwardly of the mill floor so that the roof extends beyond each side of said part of the machine, end walls positioned at the ends of the roof, one end wall having an opening to provide for the entry of the web to the other and an opening for the exit of the web passing from the machine, longitudinal side walls substantially coextensive in length with the said roof and joining said end walls at each end, said side walls extending from adjacent the outer marginal side portions of the roof to a plane substantially above the mill floor, thereby providing an open area between the lower margin of each of the side walls and the mill floor which is substantially coextensive in length with that of the side wall blower means, air slots positioned below and longitudinally of the said side walls substantially coextensive in length with the said open area, being adjacent the mill floor and being arranged to discharge air upwardly, means communicating said blower means with said air slots, means for actuating said blower means whereby air at relatively high velocity in the form of an air curtain is blown across each said open area in a direction to pass inwardly of the outer face of the adjacent said side wall, other means for supplying a major part of the drying air to the machine, means for exhausting from the upper interior portion of the closure formed by the roof and walls the air supplied by said major air-supplying means and that supplied to form said air curtain together with the water vapor resulting from the drying operation, said air-supplying means being formed and adapted to supply air in such volume and velocity as to maintain such a balance between the space within the side walls and air curtains and that outwardly thereof as will prevent the flow of more than a relatively small volume of air from the mill into said closure through the areas covered by said air curtains.

5. The arrangement set forth in claim 4 together with means for heating at least the major part of the drying air.

6. Apparatus for use in combination with a paper-drying machine having at least a substantial portion extending above a mill floor, said portion being positioned over an opening in the mill floor communicating with an underlying area, said apparatus comprising a roof extending over the top of that portion of the paper-drying machine which extends above the mill floor and being of greater width than said machine portion so as to extend beyond each side thereof, end walls positioned at the ends of the roof, one end wall having an opening to provide for the entry of the web to and the other an opening for the exit of the web passing from the machine, longitudinal side walls substantially coextensive in length with the said roof and joining said end walls at each end, said side walls extending from adjacent the outer marginal side

portions of the roof to a plane substantially above the mill floor, thereby providing an open area between the lower margins of the side walls and the mill floor, which is substantially coextensive in length with that of the side walls, blower means, air slots positioned below and longitudinally of the said side walls being adjacent the mill floor and being arranged to discharge air upwardly, means communicating said blower means with said air slots, means for actuating said blower means whereby at relatively high velocity in the form of an air curtain is blown across said open areas in a direction to pass inwardly of the outer side of said side walls, means for supplying the major portion of the drying air to the machine through said first mentioned floor opening, means for exhausting, from the interior portion beneath the roof, the air supplied to the machine through said mill floor opening and by said air forming the air curtains together with the water vapor resulting from the drying operation, said air-supplying means being formed and adapted to supply air in such volume and velocity as to maintain a balance between the space inwardly of the curtains and walls and that outwardly of said open area below the side walls as will prevent the flow of more than a relatively small volume of air from the mill in a direction to be discharged by said exhaust means.

7. The arrangement set forth in claim 6 together with means for heating at least the major part of the drying air.

8. The arrangement set forth in claim 6 in which the means for supplying the major part of the drying air comprises a chamber underlying the mill floor opening at the top into said mill floor opening and including blower means for discharging air into said chamber for passage through said floor opening.

9. Apparatus for use in combination with a paper-drying machine having at least a substantial portion extending upwardly of a mill floor, said apparatus comprising a roof extending over the top of the machine and being of greater width than that portion of the machine which extends upwardly of the mill floor so that the roof extends beyond each side of said portion of the machine, end walls positioned at the ends of the roof, one end wall having an opening to provide for the entry of the web to the machine and the other an opening for the exit of the web passing from the machine, longitudinal side walls substantially coextensive in length with the said roof and joining said end walls at each end, one of said side walls extending from adjacent the outer marginal side portions of the roof substantially to the mill floor and the other to a plane substantially above the mill floor, the latter thereby providing an open area between its lower margin and the mill floor which is substantially coextensive in length with that of the superposed side wall portion, blower means, air slots positioned below and longitudinally of the said second mentioned side wall portion being adjacent the mill floor and being arranged to discharge air upwardly, means communicating said blower means with said air slots, means for actuating said blower means whereby at relatively high velocity in the form of an air curtain is blown across said open area in a direction to pass inwardly of the outer side of said superposed said side wall portion, means for supplying a major part of the drying air to the closure at relatively low velocity, means for exhausting from the upper interior portion of the closure formed by said roof and walls the air supplied by said major air-supplying means and that supplied to form said air curtain together with the water vapor resulting from the drying operation, said air-supplying means being formed and adapted to supply air in such volume and velocity as to maintain such a balance between the space within the closure and that outwardly of said open area below

the said side wall as will prevent the flow of more than a relatively small volume of air from one side of the open zone between the lower margin of the side wall and the mill floor to the other.

- 5 10. The arrangement set forth in claim 9 in which the major portion of the drying machine is positioned over an opening in the mill floor communicating with an area below and the major portion of the air for drying is supplied through that opening.
- 10 11. The arrangement set forth in claim 9 in which means is provided for heating at least the major portion of the air supplied to the drying machine.
- 15 12. The arrangement set forth in claim 9 in which means is provided for heating at least the air supplied to form the air curtain.
- 20 13. The arrangement set forth in claim 9 in which the means for providing the air curtain comprises a number of operative sections and means for actuating all or any part thereof.
- 25 14. The arrangement set forth in claim 10 which includes an open top chamber underlying the mill floor opening with the open top thereof communicating the chamber space with the closure space formed by the top and side walls, and blower means forcing air into the said chamber to supply the major portion of the air for drying purposes.
- 30 15. The arrangement set forth in claim 10 which includes an open top chamber underlying the mill floor with the open top thereof communicating the chamber space with the said closure space, and blower means located in said chamber space and having structure discharging air upwardly through the mill floor to provide the said air curtain.
- 35 16. Apparatus for use in combination with a paper-drying machine comprising a plurality of heated drying rolls and having at least a substantial portion extending upwardly of a mill floor, said apparatus comprising a roof extending over the top of the machine and being of greater width than that portion of the machine which extends upwardly of the mill floor so that the roof extends beyond each side of said portion of the machine, end walls positioned at the ends of the roof, one end wall having an opening to provide for the entry of the web to the machine and the other an opening for the exit of the web from the machine, longitudinal side walls substantially coextensive in length with the said roof portion and joining said end walls at each end at least one of said side walls extending from adjacent the outer marginal side portion of the roof and terminating in a
- 40 45 50 55 60 65
- plane substantially above the mill floor, thereby providing an open area between the lower margin of the said side wall and the mill floor which is substantially coextensive in length with that of the side wall portion blower means, means for blowing air at relatively high velocity across said open area in a direction to pass inwardly of the said side wall, thereby establishing an air curtain across that area, means associating the ends of those drying rolls located in the said open area for intercepting at least a part of the radiant heat from the rolls to prevent the same from passing through said air curtain into the mill.
17. The arrangement set forth in claim 16 in which the means for intercepting at least a part of the radiant heat from the rolls comprises a disc of bright metal, spaced from one end of the roll and having the one face confronting the end of the roll, the said face being substantially black.

UNITED STATES PATENT OFFICE
CERTIFICATE OF CORRECTION

Patent No. 2,977,686

April 4, 1961

Arthur G. Stout

It is hereby certified that error appears in the above numbered patent requiring correction and that the said Letters Patent should read as corrected below.

Column 8, line 11, strike out "the air forming" and
insert the same after "and" in line 14, same column.

Signed and sealed this 3rd day of October 1961.

(SEAL)
